ELECTRIC DISCHARGE TUBE OF THE KIND
COMPRISING AN INDIRECTLY HEATED
CATHODE

Henricus Johannes de Weijer, Eindhoven, Netherlands, assignor to Hartford National Bank and Trust Company, Hartford, Conn., as trustee

Application February 17, 1949, Serial No. 76,884
In the Netherlands March 15, 1948

4 Claims. (Cl. 313—331)

1

The invention relates to an electric discharge tube having a cathode of the indirectly heated type comprising a cylindrical sheath in which one or more heating wires are housed and in which the space between the sheath and the heating wires, at least adjacent the ends of the cathode, is fully filled with insulating material.

It has been found that the ends of the heating wires which emerge from the insulating material at the ends of the cathode frequently break off at the area where the said heating wires emerge from the insulating material, on being bent to connect them to the supply conductors. Since we are always here concerned with comparatively thin heating wires which by themselves may be readily bent, this phenomenon could not be foreseen.

The phenomenon is particularly inconvenient with cathodes of the indirectly heated type produced by mechanical operation, such as swaging, rolling and drawing of a complex conductor, the space between the conductors being consequently filled with strongly compressed pulverulent insulating material. Although the heating wires for such cathodes may be very thin, so that bending thereof should prove to present no difficulty, the said phenomenon is found to occur to an even marked extent.

The difficulty may be obviated, if, in accordance with the invention, with an electric discharge tube comprising a cathode of the indirectly heated type which comprises a cylindrical sheath in which one or more heating wires are provided and in which the space between sheath and heating wires, at least adjacent the ends of the cathode, is completely filled with insulating material, the ends of the heating wires which ends protrude from the insulating material, are flattened, at least in part, starting at a slight distance from the point at which these ends protrude from the insulating material.

The flattened part as distinct from the remaining part of the heating wire, is found to have greater flexibility such that that part of the heating wires which protrudes direct from the insulating material is no longer bent out of shape and breakage is avoided. An explanation is that the material of the heating wires which, as a rule, is comparatively brittle, may, in addition, become less brittle due to the flattening operation. Whatever the explanation of the effect of the embodiment of the invention may be the result proves to be efficacious.

It is known to construct supply conductors outside the tube as rigid contact pins and inside the tube as flexible strips, the union between rigid

2

pin and flexible strip being, for example, in the seal. However, in the latter case, if thin wires were concerned, the phenomenon required to be avoided by the invention is liable to occur even with this known construction. However, owing to the thickness of the conductors, in this known construction cracking of the glass is more likely to occur than breakage of the conductors. Moreover, the material of such supply conductors is not so brittle as that of thin heating wires for cathodes. It is furthermore known to provide a grid stay wire with a thin flexible connecting wire. Also in this case the above problem does not arise.

15 In order that the invention may be more clearly understood and readily carried into effect, it will now be described more fully with reference to the accompanying drawing, in which:

Fig. 1 shows a tube and

20 Figs. 2, 3 and 4 are detail views of cathodes according to the invention.

Referring to Fig. 1, 1 designates the bulb of a tube, which is sealed by a bottom 2 in which contact pins 3 are sealed.

25 Arranged in the tube is an electrode system 4 comprising a bifurcated cathode 5 of the indirectly heated type constituted by a sheath 6 which is coated with emissive material and which forms an equipotential body (Fig. 2). The sheath 6 contains insulating material 7 and a heating wire

30 8 which is flattened at the end at 9. As is shown in Fig. 2, the flattened part 9 begins at a slight distance from the point at which the heating wire emerges from the insulating material, so that there is still a non-deformed part 10. Owing to 35 the great flexibility of part 9, part 10 does not bend, so that rupture at the area at which the wire emerges from the insulating material is prevented.

40 In order to assist in welding the flattened end to a vertical supply conductor, this end may be torsioned as is shown in Figs. 1 and 2. However, in this case it is also possible to flatten the end of the heating wire for part of its length only

45 and to leave the end 11 (Fig. 3) undeformed or several flattened parts (Fig. 4) may be provided, the heating wire end being flattened at several areas in various directions, so that it is adapted to be flexibly bent in all directions without the 50 part 10 being bent out of shape. Referring to Fig. 4, parts 9 and 13 are flattened in directions at right angles to one another, whereas part 12 may remain undeformed.

It is obvious that even other embodiments of the invention are possible.

What I claim is:

1. An electron discharge tube comprising an envelope having a bulb portion and a base portion, an electrode structure including an indirectly heated cathode body mounted in said bulb portion, an outer conductive sheath on said cathode body, a thin flexible heating wire in said sheath and having an end portion extending out of said sheath at an extremity thereof, and a mass of compressed pulverulent insulating material filling the space between said heating wire and said sheath at said extremity, a supply conductor positioned on said base portion, said thin flexible heating wire having a flexible flattened portion electrically connecting said supply conductor and the said extended end portion of said thin flexible heating wire.

2. An electron discharge tube comprising an envelope having a bulb portion and a base portion, an electrode structure including an indirectly heated cathode body mounted in said bulb portion, an outer conductive sheath on said cathode body, a thin flexible heating wire in said sheath and having opposing end portions, each extending out of said sheath at an extremity thereof, a mass of compressed pulverulent insulating material filling the spaces between said heating wire and said sheath at a said extremity of said sheath, and supply conductors positioned on said base portion, said thin flexible heating wire having flexible flattened end portions at opposing ends thereof electrically connecting each of said supply conductors and one of said extended end portions of said thin flexible heating wire.

3. An electron discharge tube comprising an envelope having a bulb portion and a base portion, an electrode structure including an indirectly heated cathode body mounted in said bulb portion said body having a substantially U-shape, an outer conductive sheath on said cathode body, a thin flexible heating wire in said sheath and having opposing end portions extending out of said sheath at opposite extremities of said sheath, a mass of compressed pulverulent insulating ma-

terial filling the spaces between said heating wire and said sheath at each said extremity, and supply conductors positioned on said base portion, said thin flexible heating wire having flexible flattened end portions at opposing ends thereof electrically connecting each of said supply conductors and one of said extended end portions of said thin flexible heating wire.

5. An electron discharge tube comprising an envelope having a bulb portion and a base portion, an electrode structure including an indirectly heated cathode body mounted in said bulb portion, an outer conductive sheath on said cathode body, a heating wire in said sheath and having an end thereof extending out of said sheath at an extremity thereof, a mass of compressed pulverulent insulating material filling the space between said heating wire and said sheath at said extremity, a supply conductor positioned on said base portion, a first flexible flattened member integral with said heating wire adjacent the said extended end of said heating wire, and a second flexible flattened member integral with said heating wire and electrically connected with and extending at substantially right angles to said first flattened member and interposed between said first member and said supply conductor.
